(57) **CLAIM**

The ornamental design for a film sticking device as shown and described.

DESCRIPTION

FIG. 1 is a front, right, and top perspective view of a film sticking device, showing my new design;

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an exploded view thereof.

The broken lines shown in the drawings are included for the purpose of illustrating portions of the film sticking device that form no part of the claimed design.
